COMBINED PORTABLE STOOL AND CARRYING CASE

John C. Keady, San Diego, Calif.

Application April 20, 1953, Serial No. 24,577

Term of patent 14 years

(Cl. D15—1)

To all whom it may concern:

Be it known that I, John C. Keady, a citizen of the United States, residing at San Diego, county of San Diego, State of California, have invented a new, original, and ornamental Design for a Combined Portable Stool and Carrying Case, of which the following is a specification, reference being had to the accompanying drawing, forming a part hereof.

Figure 1 is a perspective view of a combined portable stool and carrying case in the assembled condition with the end flap open, showing my design. Figure 2 is a perspective view, from above, with the end flap closed. Figure 3 is an end elevational view of the device showing the end flap open and the detachable leg sections stored in the carrying case.

I claim:

The ornamental design for a combined portable stool and carrying case, substantially as shown.

JOHN C. KEADY.
